UNITED STATES PATENT OFFICE.

JAMES M. WEED, OF PITTSFIELD, MASSACHUSETTS, ASSIGNOR TO GENERAL ELECTRIC COMPANY, A CORPORATION OF NEW YORK.

TRANSFORMER.

1,170,201.

Specification of Letters Patent.

Patented Feb. 1, 1916.

Application filed August 7, 1912. Serial No. 713,845.

To all whom it may concern:

Be it known that I, JAMES M. WEED, a citizen of the United States, residing at Pittsfield, county of Berkshire, State of Massachusetts, have invented certain new and useful Improvements in Transformers, of which the following is a specification.

My invention relates to transformers. Its objects are the improvement of the ventilation and mechanical strength of transformers and the production of a novel means for handling a transformer and holding it in its place in its tank. In order to accomplish the first of these objects, I build the core of the transformer in a plurality of sections of novel construction and combine these core sections together in a novel manner to form the complete core. The peculiar construction of the core allows the use therewith of a novel and desirable means for holding the whole transformer in position.

The sections comprising the core are provided with curved inner and outer surfaces on the center legs. By assembling these sections so that the centralmost of the corresponding edges of the various sections are displaced from each other, I produce a core having ventilating spaces extending from the bottom to the top near its center. The most central space or opening may be of sufficient size to contain the rod of the holding means later described. By reason of the curved inner surfaces on the center legs, the inner coil may be drawn tightly against these surfaces without subjecting the insulation of the coil to the undue strains of sharp bends during winding. Such a relation of coil and core obviously tends to produce a mechanically strong transformer.

The novel holding and carrying means in general consists of a rod extending through the center of the transformer having attached to it two clamping members for engaging the ends of the transformer core. This rod provides a simple means for handling the transformer and for attaching it to the tank.

The drawings which form a part of this specification illustrate a transformer involving my invention.

Figure 1 is a sectional view through the casing looking downward on the top of the transformer; Figs. 2 and 3 illustrate in perspective two possible dispositions of the

laminæ of the various sections; Fig. 4 is a 55 vertical section on the line $\alpha-\alpha$ (omitting for clearness the corner of one core section) showing particularly the means I employ for holding the entire transformer in its place in the casing; and Fig. 5 is a sectional view 60 of a part of a core showing a modification.

The core of the transformer illustrated is composed of a plurality of sections. The outer and inner surfaces a and b of the inner leg of each core section I desire to have 65 curved or at least depart from single planes; the surface b should conform preferably to the arc of a circle having the center of the transformer as a center. By preference I construct each section of the transformer 70 core of laminæ initially of uniform width of the shapes shown in Figs. 2 and 3. It will be seen that the laminæ are of two general shapes, an L-shape, 1, and a rectangular shape, 2, the corners being cut off according to the prevailing practice. I construct the sections in general of the L-shaped laminæ. These laminations 1 are fanned away from the first lamina or laminæ at one side by inserting the laminæ 2 in suitable 75 numbers in the outer leg of each core section as shown in Fig. 1. The individual laminæ are thus disposed along approximately radial lines relative to the transformer coils, as will also be seen in this figure. The 80 laminæ with respect to the joints may be related in various ways. Two desirable arrangements are shown in Figs. 2 and 3. The L-shaped laminæ 1 are placed with two joints together and the next two joints offset. Inserted laminæ 2 may then be placed as shown in Fig. 2 between adjacent laminæ 85 having offset joints, or as shown in Fig. 3 between laminæ having adjacent joints. The insertion of the laminæ 2 and the fanning caused thereby, it will be seen, produces 90 as many ventilating spaces 3 in the cross members as there are laminæ 2. The laminæ 1 are offset relatively longitudinally to produce the curved surfaces on the inner and outer legs of the core sections as shown in 95 Fig. 1.

The entire core of the transformer illustrated is composed of three core sections constructed as above described. When the sections are put together to form the entire core the edges of the center legs are offset or displaced from each other, as shown in Fig. 100 105.

1, to provide the triangular shaped opening 4 and the spaces 5 and 6. Each of the most central corresponding side edges of the center legs is displaced along an outer surface of another leg. Through these openings the cooling fluid readily passes and by them the ventilation of the entire structure is aided. It will be apparent from an inspection of Fig. 1 that the inner surfaces *b* 10 of the center legs of the sections are designed to be approximately arcs of the same circle, and hence coils without sharp bends may be used. This allows a more solid mechanical construction and the insulation 15 of the coils is not subjected to as heavy strains during winding as is common in other forms of construction where sharp bends occur. In the particular construction shown, each winding is made up of two coils 20 8, 8' and 9, 9' which may be wound directly on the core. These coils may be spaced relatively by the usual space blocks 10 as shown in the drawing and as has heretofore been common; liberal ventilating spaces are thus 25 provided therebetween. Space blocks 11 are advantageously used to help hold the core sections and the laminations thereof in place.

It will be understood that while the outer 30 and inner surface *a* and *b* of the inner legs have been described as curved, that the element of these surfaces is not a perfect curve. Since these surfaces are produced by offsetting the laminæ of each section relative to 35 each other, the surfaces are of necessity composed of a plurality of plane surfaces. The surfaces of the edges of the laminæ are offset from each other. My invention is not limited to the offsetting of each lamina relative to its adjacent laminæ as it is obvious 40 that certain advantages of my invention may be secured by making the "curved surfaces" of a plurality of plane surfaces where each plane surface is of a more appreciable width, although this may be at the sacrifice 45 of area of ventilating space. Fig. 5 illustrates a construction where the surfaces *a* and *b* on the inner legs are each made up of a plurality of plane surfaces. By the 50 term "departing from a single plane," etc., in the claims, all such constructions are obviously included. It will be noticed that in the construction illustrated in Fig. 5 there are no ventilating spaces corresponding to 55 the ventilating spaces 5, 6 and 7 of Fig. 1, these ventilating spaces having been sacrificed in this case.

With this construction of the transformer a novel means of holding the same in place 60 in the tank may be used. For a holding means, I provide a rod 12 carrying upper and lower clamping members 14 and 15 and the terminal board 13 if desired. This rod passes through the center opening 4 in the 65 core. The terminal board 13 and the clamp-

ing members 14 and 15 may be attached in any desirable way to this rod. I prefer to make the attachment a screw threaded one since such an attachment readily allows the clamping members to be brought into firm engagement with the transformer body. The clamping members are of a general three-legged construction with a leg engaging with each core section. Each leg of the upper member is of such length as to engage 70 the side of the tank, as shown at 16, to aid in maintaining the transformer in position. To further aid in maintaining the transformer in position, I have provided projections 17 on the lower clamping member 15. 8 These projections rest in depressions in the base of the tank.

The rod 12 may be held stationary relative to the tank in any desired way. I find it convenient and satisfactory to provide 8 sockets 18 and 19 in the top and bottom members of the tank respectively to receive the ends of the rod. Gaskets 20 may be provided between the end of the rod and the tank. With this construction the transformer may be assembled and held on the rod 12 by means of the clamping members 14 and 15. The whole may then be handled readily and placed within the tank; when the cover of the tank is attached in position, it is apparent that the transformer is firmly held in place.

What I claim as new and desire to secure by Letters Patent of the United States, is,—

1. A transformer core section composed of laminations of substantially the same size, offset relatively longitudinally to produce surfaces on the legs each departing from a single plane, and additional laminations inserted in one leg between the other laminations, the laminations on one side of the core section being unchanged in shape and the remaining laminations being gradually bent or fanned away from this side to make room for the additional laminations.

2. The combination of a plurality of core sections forming a transformer core, each including a center leg the outer surface of which departs from a single plane, the sections being symmetrically grouped with the center legs together, one edge of the outer surface of the center leg of each section being located nearer the center of the core than the other and being displaced from the corresponding edges of the other sections, along the outer surface of another center leg.

3. A transformer core comprising three sections, each section including a center leg and being composed of laminations initially of uniform width offset relatively longitudinally and fanned away from one side of the section, the sections being assembled with the center legs of the sections at the center of the core and with one edge of the outer surface of the center leg of each sec-

tion nearer the center of the core than the other and displaced from the corresponding edges of the other sections.

4. The combination of a transformer having a laminated core providing a complete magnetic circuit, a rod extending through the transformer core at approximately its center, core clamping plates carried by said rod engaging and supporting the core at its opposite ends and clamping its parts together, and a tank for the transformer provided with means for supporting the rod by engaging its ends.

5. The combination of a transformer having a laminated core providing a complete

magnetic circuit, a rod extending through the transformer at approximately its center, core clamping plates carried by said rod and engaging and supporting the core at its opposite ends and clamping its parts together, and a tank for the transformer provided with means for supporting the rod by engaging its ends, the walls of the tank engaging one of the clamping plates. 20

In witness whereof, I have hereunto set 25
my hand this 5th day of Aug., 1912.

JAMES M. WEED.
